DESIGN FOR A REGULATOR HANDLE FOR VEHICLE DOORS

Burton S. Floraday, Toledo, Ohio, assignor to
Detroit Harvester Company, Detroit, Mich., a
corporation of Michigan

Application June 30, 1941, Serial No. 101,798

Term of patent 7 years

To all whom it may concern:

Be it known that I, Burton S. Floraday, a citizen of the United States and a resident of Toledo, Lucas County, Ohio, have invented a new, original, and ornamental Design for a Regulator Handle for Vehicle Doors, of which the following is a specification, reference being had to the accompanying drawing forming a part thereof.

In the drawing:

Figure 1 is a top plan view of the vehicle door handle showing my new design; and

Figure 2 is a side elevation of the handle shown on Figure 1.

I claim:

The ornamental design for a regulator handle for vehicle doors, as shown.

BURTON S. FLORADAY.
